CIGARETTE LIGHTER

Beauford E. Steely, 11305 Wyatt, Dallas, Tex.

Filed Apr. 6, 1965, Ser. No. 84,638

Term of patent 14 years

(Cl. D48—27)

FIG. 2

FIG. 3

FIG. 1

FIG. 4

FIG. 5

FIGURE 1 is a front elevational view of the cigarette lighter of this invention; the opposite side being a mirror image of the side shown, except for the omission of both the indentation surrounding the flint opening and the flint opening plug near the top center.

FIGURE 2 is a top plan view of the device shown in FIGURE 1.

FIGURE 3 is one end elevational view of the device of FIGURE 2.

FIGURE 4 is the other end elevational view of the device of FIGURE 2.

FIGURE 5 is a bottom view of the device of FIGURE 2.

I claim:

The ornamental design for a cigarette lighter, as shown and described.
